US0D1080159S

(12) **United States Design Patent** (10) Patent No.: **US D1,080,159 S**
(45) Date of Patent: ** Jun. 24, 2025

(54) **FOOTWEAR SOLE**

(71) Applicant: **Wolverine Outdoors, Inc.**, Rockford, MI (US)

(72) Inventor: **Brenton Scott Wehrmeyer**, Grand Rapids, MI (US)

(73) Assignee: **Wolverine Outdoors, Inc.**, Rockford, MI (US)

(**) Term: **15 Years**

(21) Appl. No.: **29/889,036**

(22) Filed: **Apr. 7, 2023**

(51) LOC (15) Cl. **02-04**

(52) U.S. Cl.

USPC **D2/947; D2/953**

(58) **Field of Classification Search**

USPC ..... D2/902, 906, 908, 916, 918, 925, D2/946–962, 977; 36/3 B, 22 R, 24.5, 36/25 R, 28, 32 R, 34 R, 59 C, 67 A, 103 CPC A43B 13/00; A43B 13/02; A43B 13/023; A43B 13/026; A43B 13/04; A43B 13/08; A43B 13/10; A43B 13/12; A43B 13/14; A43B 13/141; A43B 13/143; A43B 13/16; A43B 13/18; A43B 13/181; A43B 13/187; A43B 13/189; A43B 13/20; A43B 13/22; A43B 13/223; A43B 13/24; A43B 13/28; A43B 13/30; A43B 13/32; A43B 13/34; A43B 13/36

(57) **CLAIM**

The ornamental design for a footwear sole as shown and described.

DESCRIPTION

FIG. 1 is a left perspective view of the footwear sole embodying the new design;

FIG. 2 is a right perspective view thereof;

FIG. 3 is a bottom view thereof;

FIG. 4 is a top view thereof;

FIG. 5 is a left side view thereof;

FIG. 6 is a right view thereof;

FIG. 7 is a front view thereof; and,

FIG. 8 is a rear view thereof.

The broken lines in the figures show portions of the footwear sole that form no part of the claimed design.

1 Claim, 8 Drawing Sheets
